US00D913229S

(12) **United States Design Patent** (10) Patent No.: **US D913,229 S**
(45) Date of Patent: **** Mar. 16, 2021**

(54) **HEATER FOR HEATING SEMICONDUCTOR WAFER**

(71) Applicant: **Tokyo Electron Limited**, Tokyo (JP)

(72) Inventor: **Toshiki Kobayashi**, Fuchu (JP)

(73) Assignee: **TOKYO ELECTRON LIMITED**, Tokyo (JP)

(**) Term: **15 Years**

(21) Appl. No.: **29/709,587**

(22) Filed: **Oct. 15, 2019**

(30) **Foreign Application Priority Data**

Apr. 24, 2019 (JP) 2019-009163

(51) LOC (13) Cl. **13-02**

(52) U.S. Cl.

USPC **D13/117**

CLAIM

The ornamental design for a heater for heating semiconductor wafer, as shown and described.

DESCRIPTION

FIG. 1 is a perspective view of a heater for heating semiconductor wafer, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
